UNITED STATES PATENT OFFICE.

MICHAEL O'DONNELL, OF LONG ISLAND CITY, NEW YORK; ELLEN O'DONNELL ADMINISTRATRIX OF SAID MICHAEL O'DONNELL, DECEASED.

BOILER CONSTRUCTION.

Application filed July 29, 1926. Serial No. 125,783.

This invention relates to the class of boilers or furnaces, and has particular reference to boilers and furnaces used for heating dwellings.

5 The principal object of the present invention is to provide a boiler or furnace of the indicated character with an outer wall structure to define a heat chamber in communication with the combustion chamber 10 and the usual uptake and other flues, to the end that gases of combustion will be caused to properly travel or circulate in the presence of a comparatively greater heating surface, resulting in greater thermal efficiency and economy in the use of fuel.

With the foregoing, other objects of the invention will appear from the embodiment of the invention which by way of example is described in the following specification 20 and illustrated in the accompanying drawings, in which

Figure 1 is a sectional elevation of a boiler embodying the present invention.

Fig. 2 is a sectional view taken on the line 2—2 of Fig. 1 and looking in the direction indicated by the arrows.

Fig. 3 is a horizontal sectional view taken substantially on the line 3—3 of Fig. 2.

The illustrated embodiment of the present invention is practiced in conjunction with a sectional boiler of a certain type which will be hereinafter described in a general way to give an understanding of the invention, and it is to be understood that the invention may 35 be practiced with other types of boilers or furnaces used for heating purposes.

The boiler is made up of sections and essentially includes by virtue of the structural features thereof, a combustion chamber 10, upakes 11 which communicate respectively with flues 12, and the latter communicating with a flue 13, as at 14. The walls of each of the sections provide the usual water space 15.

45 In accordance with the present invention the boiler is provided with an outer wall structure 16 which defines a heat chamber 17 indirectly in communication with the combustion chamber 10. The heat chamber has 50 provided therein a baffle or dividing wall 18 which combines with the wall structure 16 to define an upper heat section and a lower heat section which communicates with the upper heat section at 19 at each side. The 55 heat chamber 17 defined by the wall struc-

ture 16 occurs over the top, back and opposite sides of the boiler. Therefore, there will be a top space 20, a back space 21, and side spaces 22. The rear wall section of the structure 16 has an outlet 23 to which the 60 chimney flue is connected. The baffle or dividing wall 18 is substantially U-shaped in plan and is arranged below the outlet 23 and above the flue 13 at the rear. A leg of the baffle 18 extends substantially horizontally in each of the side spaces 22 and terminates short of the front wall section of the structure 16 to provide the passage 19. The rear leg of the baffle 18 consists of portions which slope downwardly from the outlet 70 23.

In order to make provision for cleaning out the heat chamber 17, the heat chamber at the bottom thereof at the back and sides is provided with clean-out doors 24, each 75 of which is hingedly connected as at 25 and held in a closed position by suitable latching devices 26. Clean-out openings closed by removable covers 27 are provided which give access to the lower section of the heat chamber so that brushes or other cleaning implements may be wielded in the chamber to remove the products of combustion which may be dropped out by opening the door 24.

When the combustion chamber 10 is fired, 80 the gases of combustion will issue from the combustion chamber, pass upwardly through the up-takes 11 to the flues 12, will travel forwardly of the flues 12 to the flue 13, then rearwardly in the flue 13 to a point beneath the sloping portions of the baffle 18 which direct the gases downwardly and laterally of the back space 21. From the back space 21 the heat travels forwardly in the side spaces 22 and upwardly through the passages 19 to the top space 20 and thence rearwardly therein to the back space above the baffle 18 out through the outlet 23. The particular arrangement of heat spaces is 85 such that a ready circulation of the gases of combustion or heat is possible, and due to the fact that the heat travels in the presence of a comparatively greater heating surface, there is obtained a greater thermal efficiency 90 and a saving in fuel as well.

The outer surfaces of the wall structure 16 are covered with suitable heat insulating material 28 of any preferred kind to prevent unnecessary loss of heat by radiation.

Means may be provided for blowing the 110

soot which collects in the space 20, 22 into the back of the boiler. I have illustrated the use of an approximately inverted U-shaped steam pipe 40 overlying the boiler 5 near the front end thereof, and formed with arms 41 depending into the side spaces 22. A T-coupling 42 at the intermediate portion of pipe 40 connects the latter with the front boiler section, and any suitable valve (not 10 shown) regulates the flow of steam through the coupling into the pipe. Steam spray jets such as 43 arranged at intervals along the length of pipe 40 and discharging rearwardly, serve to clean the soot out of the 15 boiler, and blow it into the rear air space where it may be removed through the door 24. The soot blower is operated whenever cleaning becomes necessary.

I claim:

- 20 1. A boiler characterized by an outer wall structure defining a heat chamber, and a baffle wall in the heat chamber dividing the same into an upper section and a lower section in communication with the upper section, the upper section in communication with the chimney flue, and the lower section in communication with the combustion chamber, said last communication including up-take flues.
- 25 2. A boiler characterized by a heat insulated outer wall structure defining a heat chamber extending around the top, back and sides of the boiler, a baffle wall in the heat chamber dividing the same into an upper 30 section and a lower section in communication with the upper section, the upper section in communication with the chimney flue, and the lower section in communication

with the combustion chamber, said last communication including up-take flues. 40

3. A boiler characterized by an outer wall structure defining a heat chamber, and a baffle wall in the heat chamber dividing the same into an upper section and a lower section in communication with the upper section, the upper section in communication with the chimney flue, and the lower section in communication with the combustion chamber, said last communication including up-take flues, said wall structure including 45 clean-out closures. 50

4. A boiler characterized by an outer wall structure defining a heat chamber at the top, back and sides of the boiler, a baffle extending in the back and sides of the heat 55 chamber which divides the heat chamber into an upper section consisting of the top and portions respectively of the back and side of the heat chamber defined, a lower section consisting of portions respectively of 60 the back and the sides of the heat chamber defined, the lower section in communication with the upper section, the upper section in communication with the chimney flue above the baffle, and the lower section in communication with the combustion chamber, said last communication including up-take flues, the heat issuing from the combustion chamber passing through said up-take flues, then 65 to the back of the heat chamber below the baffle, then downwardly and laterally to the sides, then forwardly in the sides, then upwardly to the top, then rearwardly in the top, and finally out through the chimney flue. 70

MICHAEL O'DONNELL.
